INTERNAL COMBUSTION ENGINE

Merrill C. Pletcher, Elkhart, and Melvin A. Hochstetler, Nappanee, Ind.

Application January 6, 1941, Serial No. 373,370

6 Claims. (Cl. 123—51)

The object of our invention is to provide a novel internal combustion engine having a cylinder open at each end containing dual opposed pistons; to provide means for injecting a predetermined amount of fuel between the pistons through a port opening at the center of the cylinder; to utilize compression ignition to ignite the fuel and to deliver power to both pistons simultaneously, whereby power is transmitted to opposite sides of the crank shaft thereby delivering the impact on the crankshaft and making a balanced engine.

It is our object to provide an engine having dual opposed pistons and operated as a Diesel type engine, whereby to reduce fuel expense and increase its power with a minimum amount of vibration and loss of power for this type of engine; or alternatively to provide an engine having conventional spark ignition to ignite the fuel delivered through a port at the center of the cylinder between dual opposed pistons in a single cylinder open at each end.

It is also an important object of our invention to provide a novel bifurcated lever operatively connecting the piston rods and connecting rods actuating the crankshaft, whereby the expense of manufacture is reduced and increased efficiency is gained through elimination of wear due to the reduction in the number of separate parts necessary, while at the same time increasing the strength of this element by making stub shafts integral with the lever to pivotally support it. Its construction also makes more accurate delivery of power possible.

An important object of our invention is to provide a more compact engine, whereby there will be a reduction both in the weight of the engine and in the space which it occupies, in part due to the shape of the bifurcated lever and the manner of mounting it, and reducing the weight of the engine frame.

Another object of our invention is to reduce the expense of maintenance of the engine by making these bifurcated levers interchangeable, and providing a crankshaft so arranged as to make this possible.

It is also our object to provide a lever having bifurcated upper ends supplying means of connecting two piston rods to two pistons, while the lower end connects one connecting rod or pitman to one crank of the crankshaft, the center of the bifurcated lever having integral stub shafts which seat in bearings on the frame of the engine.

It is also our object to provide the novel combination and arrangement of elements shown and described.

We attain these and other objects of our invention by the apparatus illustrated in the accompanying drawings, in which—

Figure 1 is a side elevation of our engine;

Fig. 2 is a vertical section through same;
Fig. 3 is a vertical section through a portion of our engine showing this invention applied to an engine using spark ignition; and
Fig. 4 is an end view of the crank.

Like numerals designate like parts in each of the views.

Referring to the accompanying drawings we provide an engine frame 1 having a cylinder 2. Bearings 3 are preferably integral with frame 1 and have separate caps 3a adapted to receive the stub shafts 4 which are integral with the enlarged portion 5 at or near the center of the bifurcated lever 6 which operatively connects piston rods 9 at the upper ends and connecting rods or pitman 15 at the lower end of said lever 6. Bearings 3, as shown in Fig. 3, are disposed directly beneath the end portion of the engine frame to provide a compact structure and also to reduce the material required in manufacture. Opposed dual pistons 7 are mounted in aligned position in the cylinder 2, and are operatively connected to piston rods 9 by wrist pins 10, while pins 11 pivotally connect piston rods 9 with the bifurcated lever 6, as shown in Fig. 2.

The lower legs 12 of bifurcated lever 6 are pivotally connected with a connecting rod or pitman 15 by the pin 14, as shown in Figs. 1 and 2. Rods or pitman 15 are pivotally connected by parts 16 of crank 17 of crankshaft 18. The crankshaft 18 is supported by end bearings 19, which are integral with or affixed to the engine frame 1, as shown in Fig. 1.

As shown in Fig. 2, a cam shaft 20 carries a cam 21 which operatively engages a cam tappet 22 on push rod 23. Mounted on frame extension 24 of head construction 25 is an injector or fuel valve 26 for forced injection of a predetermined amount of fuel through a port opening into the central portion of cylinder 1. A gasket 27 is provided between head construction 25 and frame 1, as shown in Fig. 2.

An exhaust passage 29 opens out of the central portion of cylinder 1, and is controlled by exhaust valve 30 which is normally held closed by spring 31, but is operated to open position at the appropriate intervals by push rod 23. Suitable means 35 are provided for actuating the injector at appropriate times in consequence of the operation of the cam 32 or other suitable element, rotated by cam shaft 36 driven by chain 37 from other cam shaft 20.

It is within the contemplation of our invention to replace the injector shown by a conventional spark plug and intake port and intake valve if it is desired to build an engine that is not of the Diesel type, but we prefer the Diesel type for its greater power and reduced cost of operation.

In operation the fuel in predetermined

amounts is injected at predetermined intervals into the center of the cylinder through a port opening where it is ignited by high compression and simultaneously acts on the dual opposed pistons 1, which in turn, through piston rods 9, 5 levers 1, connecting rods or pitmans 15 drive crank shaft 18, thereby delivering power to two points on the crank shaft, thereby positively eliminating all vibrations caused by the shock of the explosion. Positions of crank shaft throws in 10 relation to each other are 60° apart.

As shown in Fig. 4, No. 1 crank is the starting point; No. 2 crank throw is 180° from No. 1; No. 3 crank throw is 240° from No. 1; No. 4 crank throw is 60° from No. 1; No. 5 crank throw 15 is 120° from No. 1 and No. 6 crank throw is 300° from No. 1. By this arrangement and by the use of this bifurcated lever only one crank of the crankshaft is needed for each end of each pair of cylinders open at each end; and we 20 provide a pair of cylinders open at each end, each cylinder containing two opposed pistons, thus completing a unit of a four-cycle motor, one cylinder exhausting while the other is taking fuel. The pair of upper arms of each lever 6 25 connect with the piston rods of a pair of cylinders and the pair of legs of each lever 6 connect with one connecting rod 15.

Cylinders are arranged in pairs so that pistons are simultaneously actuated by the bifurcated lever 6, one of the cylinders exhausting while fuel is being injected or fired in the other. Two cylinders constitute a unit. The engine may be made with any multiple of this unit. It is to be understood that by the use of the bifurcated lever a plurality of units can be used, and by adding cranks to the crankshaft, as many units as desired may be connected with the crank shaft.

We attain an advantage of Diesel type engines by using injected or force feed fuel and an opposed piston type of engine. The gas explosion is similar to the blow of a hammer, the power of which is spent with the impact of the blow, whereas the explosion of slow-burning fuel such as is generally used in Diesel type engines, follows the piston approximately three-fourths the length of the stroke thereby delivering a more powerful stroke. Slow-burning fuel is practical only by means of an injector such as is used in Diesel type engines.

The mechanism on opposite sides of the engine is duplicated; that is, there are like piston rods, like pivoted bifurcated levers, and like connecting rods at each end of the respective cylinders, the connecting rods however being connected at opposed portions of the crankshaft as heretofore described.

Our bifurcated levers are interchangeable which is one of the novel and advantageous features of the invention.

What we claim is:

1. In an internal combustion engine, the combination of a pair of cylinders open at each end, dual opposed pistons in each cylinder, piston rods, a pivotally mounted lever, oppositely extending stub shafts forming a part of said lever above and below its pivotally mounted portion, a pair of upwardly extending arms continuing from the upper stub shaft and operatively connected to the aforesaid piston rods, a pair of downwardly extending legs continuing from the lower stub shaft, a connecting rod actuated by said legs, and a crank shaft actuated by said connecting rod.

2. In an internal combustion engine, the combination of a pair of parallel cylinders open at each end, dual opposed pistons in each cylinder, piston rods, a pivotally mounted lever having integral opposite stub shafts, a central portion on which the lever pivots, a pair of arms extending upwardly from the upper stub shaft, a pair of legs extending downwardly from the lower stub shaft, a connecting rod actuated by said legs, a crank shaft actuated by said connecting rod, the aforesaid upwardly extending arms being outwardly curved, and the lever being pivotally mounted under the end portion of the cylinder.

3. In combination with the apparatus defined in claim 2, the engine frame having bearings disposed directly beneath the cylinders for mounting the aforesaid pivotally mounted lever, whereby to provide a compact engine unit for the purpose of reducing the weight and size of the engine.

4. In an internal combustion engine, a pair of parallel cylinders open at each end, a pair of opposed pistons in each cylinder, piston rods for each piston having integral upwardly and downwardly extending stub shafts, the upper stub shaft being bifurcated to form a pair of arms pivotally connected at their upper ends to the piston rods, the lower stub shaft being bifurcated to form a pair of legs integral with the downwardly extending stub shaft, a connecting rod actuated by said legs, a crank shaft actuated by said connecting rod, fuel being taken into one cylinder while the products of combustion are being exhausted from the other cylinder, and an injector for supplying a predetermined quantity of fuel under pressure, the pistons being arranged to move close to each other for compression ignition.

5. In an internal combustion engine, a pair of parallel cylinders open at each end, a pair of opposed pistons in each cylinder, piston rods for each piston, a bifurcated lever having a pair of outwardly curved arms actuated by the piston rods for simultaneous operation, fuel being taken into one cylinder while the products of combustion are being exhausted from the other cylinder, connecting rods actuated by the lower ends of said levers, and a crank shaft actuated by the connecting rods, and means disposed at the central portion of each cylinder for supplying fuel to and exhausting it from the respective cylinders, a cam shaft, cam tappets, push rods carrying said cam tappets, pivoted levers operated by said push rods, spring-controlled normally closed valves actuated by the push rods, and intake and exhaust ports controlled by said valves.

6. In an internal combustion engine, two pairs of parallel cylinders open at each end, a pair of opposed pistons in each cylinder, piston rods for each piston, bifurcated levers, each lever having an enlarged shank and having a pair of upwardly extending arms actuated by piston rods for simultaneous operation and also having its lower end bifurcated and terminating in legs connected to connecting rods, the shank of the lower portion of said lever also being enlarged, one pair of pistons operating on the power stroke while the other pair of pistons are operating on the exhaust stroke, a crank shaft actuated by the connecting rods, and means disposed at the central portion of each cylinder for supplying fuel to and exhausting it from said cylinder.
